KNIFE GUARD MECHANISM

Warren C. Lichty, Detroit, Mich.

Application April 17, 1935, Serial No. 16,744

18 Claims. (Cl. 30—285)

My invention relates to improvements in a guard mechanism adapted for use with a utensil such as a paring knife or similar tool; and the objects of my improvements are, first, to provide a mechanism for guarding and protecting the fingers of an operator using a knife or similar tool from being injured and irritated by contact with the blade of the knife or similar tool; second, to provide a guard mechanism for a knife or similar tool that may be readily installed on or removed from the knife or similar tool; third, to provide a guard mechanism for a knife or similar tool that will control the thickness of the paring or slice of the material being pared; fourth, to provide a guard mechanism for controlling the thickness of the paring or slice made by a knife or similar tool with means for adjusting the mechanism to provide parings or slices of different thicknesses; fifth, to provide a mechanism for a knife or similar tool that will enable the operator to develop rectangular or similar shaped parings, pieces, strips or slices from an object such as a potato to form what is commonly known as "shoestring" or "french fry" potatoes; sixth, to provide a guard mechanism for a knife or similar tool that will enable the operator to develop either a conventional slice or a string or narrow strips from said slice; seventh, to provide a guard mechanism for a knife or similar tool that will enable the operator to develop slices from an object being pared and which will leave the tip of the knife or similar tool exposed for the purpose of cutting and digging eyes from such objects as potatoes and for similar operations on similar objects; eighth, to provide a guard mechanism for a knife or similar tool that will enable the operator to use a thumb for exerting a thrust against the corner of the knife without danger from being injured thereby; ninth, to provide a guard mechanism for a knife that will enable the operator to apply a pressure from the fingers to opposite sides of the knife blade without injury, irritation, or bruising of said fingers; tenth, to provide a guard mechanism for a knife or similar tool and having a deformable portion adapted to be displaced to clear the blade of the knife to permit the knife to be used in a conventional manner without reference to the thickness of the paring or slice developed; eleventh, to provide a guard mechanism for a knife that may be used with or without a slicer mechanism adapted for associated use therewith on the knife; twelfth, to provide a slicer mechanism having resilient characteristics for gripping

the blade of a knife; thirteenth, to provide a guard mechanism having resilient characteristics for gripping the blade of a knife; fourteenth, to provide a slicer mechanism adapted to be retained on a knife by a guard mechanism mounted on the knife; and fifteenth, to provide a slicer mechanism provided with a plurality of cutters having surfaces abutting the broad side of a knife blade to absorb the thrust reaction of the cutters of the slicer mechanism.

I attain these objects by the mechanism illustrated in the accompanying drawing, in which—

Figure 1 is a plan view of my guard mechanism, which controls the thickness of conventional slices, applied to a knife; Fig. 2, a side view of the guard mechanism and a partial view of the knife disclosed in Fig. 1; Fig. 3, a sectional view of the guard mechanism and knife disclosed in Fig. 2, said sectional view being taken on the line 3—3, Fig. 2; Fig. 4, a partial plan view of the guard mechanism and knife disclosed in Fig. 1, said guard mechanism being mounted in a different adjusted position on the knife to develop a slice of greater thickness than with the guard mechanism in the position disclosed relative to the knife in Fig. 1; Fig. 5, a side view of the guard mechanism installed on a knife, disclosed partially, in association with a second mechanism for developing small slices or strips from a conventional slice of a potato or similar object; Fig. 6, an end view of my mechanism and knife as disclosed in Fig. 5, a cross section of the knife blade being disclosed; and Fig. 7, a bottom view of the mechanism and knife disclosed in Fig. 5.

Similar numerals refer to similar parts throughout the several views.

The knife 1 is provided with the handle 2 and the blade 3 and constitutes a conventional paring knife used as a kitchen utensil and indicates one of various tools or implements of similar use and construction with which my invention is adapted for use, the blade 3 being set into the handle 2 and suitably secured by the rivets or fastening members 4.

The guard mechanism comprises the convoluted portion 5 at its front or forward end which is formed by a wire wound into a plurality of coils 6 similar to the coils of a spring member, one end of the wire terminating at 7 to form a partial coil.

The wire forming the coils 6 will be extended to form the spacer portion 8 which extends between and connects and spaces the convoluted

portion 5 and the convoluted portion 9 which is formed by further coiling the wire to form the coils 10 which are located to extend beyond and cover the corner or heel 11 of the blade 3 thus preventing the thumb of the operator from engaging the heel 11, the thumb being conventionally placed adjacent the heel 11 and held, with pressure, against the lower side of the handle 2 in the usual paring and slicing operation, a condition that often results in injury to the thumb of the operator and continually occasions irritation and inconvenience due to the thumb being pressed continually against sharp edges or portions of the blade 3 or handle 2, this condition being eliminated by the thumb engaging my guard mechanism adjacent the smooth surface of the rear portion of the spacer portion 8 and the smooth lower surfaces of the convoluted portion 9, the thumb of the operator being indicated at 12, Fig. 5.

It is to be noted that the wire from which the guard mechanism is made will be further extended upwardly as at 13 and from this point the wire will be bent to form the portion 14 which extends transversely across the upper side of the knife 1 at a point substantially adjacent the junction of the blade 3 with the handle 2, the portion 14 being further bent upwardly and curved to form one side 15 of the finger or index thrust guard or flange 16, the one side of the index thrust guard 16 being inclined or bent inwardly to the curved tip or portion 17 where it is further extended to form the other side 18 of the index thrust guard 16, the sides 16 and 18 being oppositely inclined to form upwardly converging sides to present a more efficient and slightly tip portion 17, the lower portion of the side 18 being bent to form the portion 19 which extends transversely across the upper edge of the blade 3 in a plane substantially parallel with the portion 14, the portion 19 as well as one end of the wire, from which the guard mechanism is made, terminating at 20, the portion 19 contacting the upper edge of the blade 3 and forming a means for transferring the thrust of the index finger against the index thrust guard 16 to the blade 3 during the paring or slicing operation, the index thrust guard 16 being provided with a curved formation as viewed from the side, in Figs. 2 and 5, to fit and engage the index finger of the operator when the knife 1 together with the guard and slicing mechanisms are held and gripped by the hand of the operator, the index finger of the operator being indicated at 21 in Fig. 5.

It is to be noted that the blade 3 will be inserted between like coils of the convoluted portions 5 and 9 and will thus be located or spaced from the spacer portion 8 with which it extends substantially parallel, the width of the space 22 between the blade 3 and the side of the spacer portion 8, as viewed in Fig. 1, controlling the thickness of the paring or slice which will be pared or sliced from a potato or similar object, the spacer portion contacting and sliding over the outside surface of the potato or similar object during the paring or slicing operation, the space 22 representing the minimum space and consequent minimum thickness of the paring or slice due to the blade 3 being positioned between the pair of like coils, in each of the convoluted portions 5 and 9, nearest the spacer portion 8, the diameter of the wire substantially determining the increments of thickness of the paring or slice, the blade 3 being positioned between the different

like pairs of coils of the convoluted portions 5 and 9 in accordance with the desired thickness of the paring or slice, the blade 3 being disclosed as being positioned between the next pair of like coils of the convoluted portions 5 and 9 in Fig. 4, resulting in a space 24 substantially twice the width of the space 22 in Fig. 1, thus further resulting in a consequent increase in the thickness of the paring or slice.

It is to be noted that the spacer portion 8 will be positioned slightly below the cutting edge 23 of the blade 3, as viewed in Fig. 2, thus resulting in the space or gap 25 as viewed from the side in Fig. 2, the spacer portion 8 thus being positioned ahead or in advance of the cutting edge 23 so that the thumb 12 of the operator is also positioned away from and in a protected position where it cannot engage the cutting edge 23 in the normal paring or slicing operation.

However, it is to be noted that due to the flexible characteristics of the wire of which the guard mechanism is made, the spacer portion 8 may be bent, flexed, or displaced by an added pressure of thumb 12 against the spacer portion 8, to substantially the position, as indicated by the dotted lines 26, Fig. 2, and in which position of the spacer portion 8, the knife 3 may be used in a conventional manner, at the central portion of the cutting edge 23, without interference of the spacer portion 8 with the potato or similar object which is being pared or sliced, the thumb 12, during the operation, being slidably moved along the spacer portion 8 until the thumb 12 approaches or nearly approaches the longitudinal central portion of the spacer portion 8, the thumb 12 being further preferably positioned in this operation with the spacer portion 8 in contact principally with the inner side portion of the thumb relative to the cutting edge 23 of the blade 3.

It is to be noted that the blade 3 of the knife 1 is disclosed as being provided with the point or pointed portion 27 which is located and extends beyond the coils 6 of the convoluted portion 5 so that the point 27 is positioned so that it is free for digging eyes, specks, etc., out of the potato or similar object, or for similar operations with the guard mechanism mounted on the knife 1.

It is to be noted that my guard mechanism is especially adapted for use as an accessory with the knife 1 and may be readily installed thereon or removed therefrom as desired by the operator. In installing the guard mechanism on the knife 1, the point 27 of the blade 3 is inserted between the desired pair of coils 9 and then the blade 3 is slidably moved longitudinally through and between said pair of coils in a plane substantially bisecting the angular space between the index thrust guard 16 and the spacer portion 8 until the convoluted portion 9 is adjacent the forward end of the handle 2, when the guard mechanism may be pivotally moved, relative to the blade 3, about the convoluted portion 9 as a pivot center, until the convoluted portion 5 is positioned with the blade 3 between the desired pair of coils thereof and with the spacer portion 8 substantially parallel with and spaced from the cutting edge 23 as disclosed in Fig. 2, the procedure being substantially reversed to remove the guard mechanism from the knife 1.

When it is desired to produce and develop "shoe string" or "french fry" pieces, slices or strips of a potato or similar object, the slicer mechanism, comprising the wire 28 and the cutters or blades 75

29, is utilized in conjunction with the guard mechanism on the knife 1, the wire 28 being formed with the end portions 43 each having the sides 30 and 31 forming a loop or bent portion each having the open upper end 32 for receiving the blade 3 therein to position it between the sides 30 and 31 with the cutting edge 23 in contact with the closed lower end 33, the sides 30 and 31 being preferably formed with a wider space therebetween at its lower portion adjacent the closed end 33, the sides 30 and 31 being constructed with a curved formation, as disclosed in Fig. 6, which allows the upper ends of the sides 30 and 31 adjacent the open ends 32 to be positioned normally in contact with one another to allow the blade 3 to be inserted through the open ends 32, the sides 30 and 31 being necessarily spread apart to receive the blade 3 therebetween, the sides 30 and 31 inherently possessing resilient characteristics which will be increased by the spreading of the sides 30 and 31 to cause the surfaces of the sides 30 and 31, adjacent the open ends 32, to grip the blade 3 and retain the slicer mechanism on the blade 3, the wire 28 of the slicer mechanism terminating at the ends 34. The wire 28 of the slicer mechanism is provided with the portions 35 which are bent to extend outwardly and slightly downwardly from the blade 3, as viewed in Fig. 6, the portions 35 being connected by the portion 36 which extends substantially parallel with the blade 3 and in a plane extending transversely to the blade 3 between its upper edge and its lower or cutting edge 23.

The cutters 29 are provided with suitable openings, through which extends the portion 36 of the wire 28 and are spaced by the spacer, bushing or washer members 37 which are also provided with suitable openings through which extends the portion 36, the cutters 29 and the spacer members 37 being suitably secured to the portion 36 by welding, soldering or similar means.

The spacers 37 are each preferably provided with a relatively large surface 38 for contacting the cutters 29 and may be provided with a curved or spherical surface or shape extending to the relatively small end surfaces 39 to present a smooth outer surface and pleasing appearance.

The cutters 29 are constructed with a semi-cylindrical shape at the portion 44 through which the portion 36 of the wire 28 extends and are each provided with the cutting edges 40 extending substantially at right angles with the cutting edge 23, the cutters 29 being further provided with the surfaces 41 which abut the flat surface, of the blade 3, which is located nearest the operator, the remaining peripheral edges of the cutters 29 respectively connecting one end of the surfaces 41 and the cutting edges 40 longitudinally with the peripheral edges of the semi-cylindrical portions 44 through which the portion 36 of the wire 33 extends, the surfaces 41 abutting the surface of the blade 3, bracing and absorbing the thrust of the cutting edges 40 against and through the potato or similar object. It is to be noted that the spaces 42 between the spaced cutters 29, as viewed in Fig. 7, will develop and determine the width of the "shoe strings", strips, slices, or pieces of the potato or similar object while the depth of said "shoe strings", strips, slices, or pieces will be controlled and developed by the spaces 22 or 24 or similar adjusted spaces, the spaces 42 being disclosed in Fig. 7 as being rectangular with substantially equal sides to form a square, the blade 3 being positioned between the pairs of coils, in

the convoluted portions 5 and 9, located farthermost from the spacer portion 8.

It is to be noted that the portions 43 of the wire 28 of the slicer mechanism will be positioned, on the blade 3, adjacent the inner sides 5 of the convoluted portions 5 and 9 of the guard mechanism, the slicer mechanism, thus being retained longitudinally of the blade 3 by the guard mechanism.

It is to be understood that the coils of the 10 convoluted portions 5 and 9 of the guard mechanism will possess sufficient resilient characteristics to clamp and retain the guard mechanism in its operative mechanism on the blade 3 of the knife 1. 15

It is also to be noted that my mechanism provides means for resiliently attaching a guard mechanism to a blade of a knife together with resilient means for transferring a thrust of a finger to a knife blade and also provides means 20 for resiliently attaching a slicer mechanism to said blade.

In operation, the guard mechanism is assembled on the blade 3 of the knife 1 and with the convoluted portion 5 pivotally moved away from the blade, as above described, the slicer mechanism is assembled on the blade 3, after which the convoluted portion 5 may be pivotally moved to the blade 3, the blade 3 being positioned between the selected pairs of coils of the convoluted 30 portions 5 and 9 to provide the requisite thickness of the pieces of potato or similar object.

The potato or similar object is grasped in the left hand, for example, while the handle of the knife 1 is grasped in the other or right hand with the thumb 12 adjacent the lower side of the guard mechanism and the knife, the index finger 21 of the hand grasping the knife, being placed in engagement with the index finger guard 16.

The cutting edge 23 of the blade 3 of the knife 1 and the cutting edges 40 of the slicer mechanism are entered or inserted in and through the potato or similar object with the spacer portion 8 sliding over the outside of the potato or similar object, the potato or similar object being cut into pieces 45 or strips according to the size of the spaces 42.

If it is desired to accomplish only a paring or plain slicing operation, then the slicer mechanism may be omitted and the guard mechanism installed alone on the knife 1 as disclosed in Figs. 50, 1, 2, 3, and 4.

I claim:

1. In a mechanism for a knife provided with a blade and a handle for slicing a potato or similar object, the combination of a guard mechanism provided with convoluted portions at each of its ends, each of said convoluted portions comprising a plurality of coils together with a spacer portion connecting said convoluted portion and extending substantially parallel with and in spaced relationship to said blade, said spacer portion being located in a plane extending substantially at right angles to the broad surface of the blade and below its cutting edge, said spacer portion being adapted to be held in engagement with the potato or similar object during the slicing operation, the blade of the knife being adapted to be entered and frictionally held between a pair of coils of each of the convoluted portions of said guard mechanism, one of the convoluted portions of said guard mechanism being located adjacent the junction point of the blade and the handle of the knife, said last mentioned convoluted portion extending beyond the heel of the blade of the knife to protect the thumb of 75

- the operator when the knife is held in the hand of the operator for paring or slicing the potato or similar object, the other of said convoluted portions being located rearwardly from the point of the blade of the knife to leave said point free for digging eyes, specks, etc., from the potato or similar object, and a slicer mechanism provided with loop portions at each of its ends for resiliently engaging the sides of the blade of the knife 5 to secure the slicer mechanism on the blade of the knife, said loop portions being located in engagement with the inner surfaces of said convoluted portions of said guard mechanism to further retain said guard mechanism on the blade 10 of the knife, said slicer mechanism being further provided with a third portion extending in a spaced relationship with and substantially parallel with the broad surface of the blade of the knife, said slicer mechanism being further provided with a plurality of cutters mounted in spaced relationship on said third portion of said slicer mechanism and each having surfaces abutting the broad surface of the blade of the knife, said cutters each having cutting edges extending 15 adjacent the cutting edge of the blade of the knife and adapted to slice into strips the slice of the potato or similar object which is being sliced therefrom by the cutting edge of the blade of the knife.
2. In a guard mechanism for a knife provided with a blade for paring a potato or similar object, the combination of a pair of convoluted portions each provided with coils adapted to receive and frictionally hold the blade of the knife there- 20 between, a spacer portion connecting said convoluted portions and extending substantially parallel with the blade of the knife and in spaced relationship therewith to control the thickness of the paring when said spacer portion is held 25 in engagement with the potato or similar object during the paring operation, and a plurality of cutters having portions frictionally engaging and securing said cutters to said blade, said portions of said cutters being positioned between said pair 30 of convoluted portions to further retain said cutters against movement longitudinally of said blade, said cutters being adapted to slice said paring in strips.
3. In a guard mechanism for a knife provided 35 with a blade for paring a potato or similar object, the combination of a pair of convoluted portions adapted to clamp the blade of a knife, a spacer portion connecting said convoluted portions and extending in a plane located normally 40 below the cutting edge of said blade to maintain portions of the hand of the operator from the cutting edge of said blade, said spacer portion being provided with resilient characteristics to permit it to be deflected and displaced to a position where portions of it are located above the cutting edge of said blade, and a plurality of cutters having portions resiliently engaging said 45 blade, said portions of said cutters being located between and adjacent said convoluted portions 50 to prevent movement of said cutters longitudinally of said blade, said cutters being adapted to cut said paring into slices.
4. In a guard mechanism for a knife provided 55 with a blade for paring a potato or similar object, the combination of a pair of convoluted portions resiliently engaging the blade of the knife, one of said convoluted portions being provided with an extension portion extending adjacent one side only of said blade, a spacer portion 60 connecting said convoluted portions and adapted

to engage the potato or similar object, and a finger thrust portion extending above the blade of the knife, said extension portion of said convoluted portion being extended to form said finger thrust portion.

5. In a guard mechanism for a knife provided with a blade for paring a potato or similar object, the combination of a pair of convoluted portions resiliently engaging the blade of the knife, a spacer portion connecting said convoluted portions and adapted to engage the potato or similar object, and a finger thrust portion extending above the blade of the knife, said finger thrust portion being provided with a resilient portion adapted to engage the blade of the knife and to transfer the thrust of the finger to the blade of the knife during the paring operation, said convoluted portions, said spacer portion and said finger thrust portion being formed of a sole piece of wire or similar material, said finger thrust portion being extended from one of said convoluted portions.

6. In a guard mechanism for a knife provided with a blade for paring a potato or similar object, a guard mechanism comprising a wire forming a substantially straight portion located in spaced relationship to the blade of the knife together with a plurality of coils at each end of said straight portion for resiliently engaging the blade of the knife, said straight portion being adapted to engage the potato or similar object during the paring operation, one of said plurality of coils at one end of said straight portion being extended to form a finger thrust guard positioned above the knife and resiliently engaging said blade to transfer the thrust of the finger to said blade during the paring operation.

7. In a guard mechanism for a knife having a blade for paring a potato or similar object, the combination of a pair of convoluted portions adapted to resiliently engage the blade of the knife, a resilient spacer portion connecting said convoluted portions and adapted to engage the potato or similar object, said resilient spacer portion being normally located below the cutting edge of the blade of the knife, said resilient spacer portion being adapted to be displaced to a position where portions of itself will be located above the cutting edge of the blade of the knife, and a resilient finger thrust guard extending above the knife and provided with a portion for resiliently engaging the blade of the knife to transfer the thrust of the finger to the blade of the knife during the paring operation, said finger thrust guard being constructed by providing one of said convoluted portions with an extension portion extending upwardly adjacent one side only of said blade, said extension portion being further extended across the upper edge of said blade to form said finger thrust guard.

8. In a slicer mechanism for a knife having a blade for slicing a potato or similar object, the combination of a guard mechanism provided with portions for securing to said blade together with a portion for spacing said first mentioned portions, said last mentioned portion engaging said potato or similar object to control the thickness of the slice, and a plurality of cutters having portions for securing to said blade, said portions of said plurality of cutters being placed adjacent said first mentioned portions of said guard mechanism to retain said cutters longitudinally on and relative to said

blade, said plurality of cutters being adapted to cut said slice into strips, said plurality of cutters being further adapted to be removed from said blade to permit said knife to be used with said guard mechanism without said plurality of cutters.

9. In a slicer mechanism for a knife having a blade for slicing a potato or similar object, the combination of a guard mechanism provided with portions for securement to said blade, said guard mechanism being provided with a portion for engaging the potato or similar object to control the thickness of the slice, and a plurality of cutters having portions for securement to said blade, said portions of said plurality of cutters being positioned between and in substantial engagement with said portions securing said guard mechanism to said blade and to retain said cutters longitudinally of said blade, said plurality of cutters being adapted to cut said slice into strips.

10. In a slicer mechanism for a knife having a blade for slicing a potato or similar object, the combination of a mechanism secured to said blade and provided with a spacer portion for controlling the thickness of the slice, and a member mounted on said blade and provided with a portion bent outwardly from said blade together with a plurality of cutters telescopically mounted on said bent portion and located in planes extending substantially at right angles to said blade and said spacer portion to cut the slice into strips, said member being extended to form loop portions each having open sides for receiving said blade therein, said loop portions resiliently clamping said blade.

11. In a slicer mechanism for a knife having a blade for slicing a potato or similar object, the combination of a mechanism mounted on said knife and provided with a spacer portion for controlling the thickness of the slice, a member secured to said knife and provided with a portion bent outwardly from said blade, and a plurality of cutters telescopically mounted on said bent portion of said member in spaced relationship and adapted to cut said slice into strips, said plurality of cutters being provided with resilient loop portions for clamping said blade.

12. In a sliver mechanism for a knife provided with a blade for slicing a potato or similar object, the combination of a mechanism mounted on said knife and provided with a spacer portion adapted to engage the potato or similar object to control the thickness of the slice, a member provided with a portion extending parallel with the face of the knife, said member being provided with a pair of clamp portions for resiliently engaging said knife to secure said member thereon, and a plurality of cutters mounted on said portion of said member in spaced relationship to engage and cut the slice into strips.

13. In a slicer mechanism for a knife provided with a blade having a cutting edge for slicing a potato or similar object, the combination of a mechanism mounted on said knife and provided with a spacer member adapted to engage the potato or similar object to control the thickness of the slice, a wire member secured to said blade and having a portion extending substantially parallel with said blade, and a plurality of cutters mounted on said portion of said wire member in spaced relationship and each provided with a cutting edge extending substantially at right angles to the cutting edge of said blade together

with a surface abutting the broad side of said blade.

14. In a slicer mechanism for a knife provided with a blade for slicing a potato or similar object, the combination of a guard mechanism mounted on said blade, and a slicer mechanism mounted on said blade, said slicer mechanism comprising a support member formed by wire or similar material together with a plurality of cutters having surfaces abutting said blade to absorb the thrust reaction developed by said cutters in the slicing operation, said cutters being mounted on said support member formed of wire or similar material.

15. In a slicer mechanism for a knife provided with a blade for slicing a potato or similar object, the combination of a structure mounted on said blade and provided with a portion extending substantially parallel with said blade, and a plurality of cutters encircling said portion of said structure, said plurality of cutters each having an edge portion abutting said blade to absorb thrust reactions imposed on said plurality of cutters in the slicing operation.

16. In a slicer mechanism for a knife provided with a blade for slicing a potato or similar object, the combination of a guard mechanism mounted on said blade and provided with a portion for engaging the potato or similar object to govern the thickness of the slice, a member secured to said blade, a plurality of cutters mounted on said member and abutting said blade, and washer members secured to said member and spacing said cutters in their operative positions.

17. In a slicer mechanism for a knife provided with a blade for slicing a potato or similar object, the combination of a guard mechanism mounted on said blade and provided with a portion for engaging the potato or similar object to govern the thickness of the slice, and a plurality of cutters supported by a structure having a portion extending substantially parallel with said blade, said cutters having portions resiliently clamped on said blade, said plurality of cutters each encircling said portion of said structure, said cutters being spaced to engage and cut the slices into strips.

18. In a guard mechanism for a knife provided with a blade for paring a potato or similar object, the combination of a pair of convoluted portions each provided with a plurality of coils adapted to frictionally receive and hold the blade of the knife therebetween, a spacer portion connecting said convoluted portions and extending substantially parallel with the blade of the knife and in spaced relationship therewith to control the thickness of the paring, an extension portion connected with one of said coils of one of said convoluted portions, said extension portion being located adjacent one side only of said blade, said extension portion being extended to form a portion extending transversely across the upper side of said blade, said last mentioned portion being further formed to provide upwardly extending portions curved to fit a finger of the operator, one of said upwardly extending portions being further extended inwardly to form a second portion extending transversely across and in engagement with the upper portion of said blade to provide means for transferring the thrust of the finger of the operator to said blade during the paring operation.
